(57) **CLAIM**

The ornamental design for a toy cash register electronic scale as shown and described.

DESCRIPTION

FIG. 1 is a perspective view of a toy cash register electronic scale showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top plan view thereof;
FIG. 8 is a bottom plan view thereof; and,
FIG. 9 is a partial enlarged view of portion 9 in FIG. 1.
The broken lines depict portions of the toy cash register electronic scale and form no part of the claimed design.
The dash-dot-dash line is included for the purpose of illustrating the bounds of the enlarged view and forms no part of the claimed design.

1 Claim, 9 Drawing Sheets
